UNITED STATES PATENT OFFICE.

LOUIS CHRISKOS, OF MUSKEGON, MICHIGAN.

COVER OPENING AND CLOSING MECHANISM.

1,331,143.

Specification of Letters Patent.

Patented Feb. 17, 1920.

Application filed January 9, 1919. Serial No. 270,357.

To all whom it may concern:

Be it known that I, LOUIS CHRISKOS, a subject of the King of Greece, residing at Muskegon, in the county of Muskegon and 5 State of Michigan, have invented new and useful Improvements in Cover Opening and Closing Mechanism, of which the following is a specification.

The present invention has reference to 10 covers or lids for cabinets, writing desks and the like; and its object is to provide improved means for opening and closing such covers.

This object is attained by, and the invention finds preferable embodiment in, the structure hereinafter described and illustrated by the accompanying drawings, in which:—

Figure 1 is an end view of a cabinet or 20 desk, the casing whereof has been partially broken away to disclose operative parts;

Fig. 2 is a like view of the opposite end of the same;

Fig. 3 is a rear view of the same, a part 25 of the casing being broken away; and

Fig. 4 is a vertical transverse sectional view of the same taken on a plane corresponding to line A—A of Fig. 3.

In the embodiment of the invention 30 chosen for illustration by the drawings and for detailed description in the body of this specification, a cabinet 1 is shown, suitable for phonographs and the like. The chamber 2 (wherein may be mounted a phono-

35 graph, for instance) is inclosed by a movable cover 3, shown in closed position in Fig. 4. This cover may be of various well-known forms or types, as a flexible curtain, traveling in grooves or guides 4 in the ends 40 of the cabinet as shown. This cover is moved by a swingable arm 5 connected therewith, which arm is swung by reciprocal means, the manually-operated slide 6, through suitable mechanical connections.

45 These connections may be of various kinds, and in the embodiment of the invention illustrated such connections are as follows:

The arm 5 is pivotally mounted on the cabinet at 7 and is connected to the rear of 50 the cover as by the rod or pin 8. The arm has a gear 9, concentric with its pivotal mounting, with which gear meshes a second gear 10 pivotally mounted on the cabinet,

and having a third gear 11 concentric and movable fixedly therewith. A toothed segment 12 pivotally mounted at 13 on the cabinet meshes with the third gear 11. The reciprocal means or slide 6 having a manually-operating portion 15 extending outside the cabinet is connected to a lever 16 55 which is connected to the segment by a link 17. When the slide 6 is pushed down by pressure on the portion 15, the segment is turned on its pivot, the gears are rotated and the arm 5 is swung to move the cover 60 to its open position.

To close the cover, a similar second reciprocal means or slide 14 may be pushed down, whereby the lever 18 fulcrumed at 19 is turned, swinging in turn by the link 70 30 the lever 20 fulcrumed at 21 in the back of the cabinet and connected by the link 31 to the lever 23 fulcrumed at 24 and whose opposite end is connected at 25 to the slide 6. This movement of the slide 14 causes the 75 segment to turn in the opposite direction, thus closing the cover. Suitable springs 26 and 27 may be employed to counterbalance the weight of the moving parts.

It will be seen that the cover is not hing- 80 edly mounted, but is displaced as a totality in opening and closing—i. e. the cover is movable bodily.

The invention being intended to be pointed out in the claim, is not to be limited to or 85 by details of construction shown or described.

I claim:

In a structure of the character described; a cover movable bodily; a pivotally mounted 90 arm connected to the cover to move the same and having a gear; a second gear meshing with said gear; a third gear concentric with the second gear and rotatable therewith; a pivotally mounted toothed 95 segment meshing with the third gear; reciprocal means; connections between said means and the segment for pivotally moving the segment by said means.

In testimony whereof I have hereunto set 100 my hand at Grand Rapids, Michigan, this 7th day of January, 1919.

LOUIS CHRISKOS.
